UNITED STATES PATENT OFFICE.

ARTHUR B. CONNER, OF PETALUMA, CALIFORNIA.

DISPLAY RACK.

Application filed April 26, 1924. Serial No. 709,247.

This invention relates to improvements in display racks.

The principal object of this invention is to produce a display rack wherein a plurality of display boards are rotatably mounted upon a shaft and means are provided whereby each display board may be independently viewed.

Another object is to provide a structure of this character which is neat in appearance, simple to operate, cheap to manufacture, and one which will take up but a minimum amount of space.

A still further object is to provide means whereby two persons may view the display boards from opposite sides of the rack at the same time.

Other objects and advantages will be apparent during the course of the following description.

In the accompanying drawings forming a part of this specification and in which like numerals are employed to designate like parts throughout the same,

Figure I is a vertical side elevation of my device, and

Figure II is a top plan view of Figure I.

Figure III is a fragmentary detail view showing the central shaft and screen supporting ring.

I am aware of the fact that various forms of display racks have been employed, which racks could be revolved. The principal difficulty, however, with this type of rack is that it may be only viewed from one side and no particular means is provided for holding the display boards in such a position that they may be viewed from a distance. I have, therefore, sought to provide a rack which will be advantageous for displaying and at the same time overcome some of the difficulties of previous racks.

In the accompanying drawings wherein for the purpose of illustration is shown a preferred embodiment of my invention, the numeral 5 designates a pair of vertical uprights each of which is secured to cross pieces 7, the adjacent ends of which are threaded to a T 8. A similar cross piece 9 is connected to the T 8 and to an elbow 11 from which extends downwardly a brace 12.

A central shaft 13 is carried by the T 8 and has its lower extremity suitably supported in the bracket 14. This shaft 13 carries parallel spaced ring members 16 and

17 between which are pivoted display boards 18, the pivots being shown at 19 and 21.

Each of these display boards has a spring 22 connected thereto and to the shaft 13. On the uprights 5 and 12, I mount brackets 23 and 24, respectively. Each of these brackets carries a roller 26 which is adapted to contact the free edge of the display boards when they are brought into contact therewith.

A gear 28 is connected to the shaft 13 and is adapted to mesh with a gear 29 mounted upon a rod 31, the end of which is fashioned so as to form a crank 32.

With the structure thus constructed it is possible to secure to the display boards any given exhibit and then by rotating the crank 32 to cause the various boards to rotate together with the shaft 13. As the boards come into contact with the rollers 26 they will be caused to move from a radial position to the position shown in Figure 2, which results in the tensioning of the springs 22 which springs function to return the display boards to their ordinary position as soon as the free edge of the board has left the roller 26.

It will thus be seen that a rack of this character will accomplish all of the objects above set forth.

It is to be understood that the form of my invention herewith shown and described is to be taken as a preferred example of the same and that various changes in the shape, size and arrangement of parts may be resorted to without departing from the spirit of the invention or the scope of the subjoined claims.

Having thus described my invention, I claim:

1. In a device of the character described, a support, a shaft mounted on said support, spaced rings mounted on said shaft, a plurality of display boards pivoted to said rings, a spring connected to each of said boards and to said shaft, for the purpose of maintaining said boards in radial position with respect to said shaft, means for moving a plurality of said boards out of radial position with respect to said shaft, said means comprising a roller adapted to contact the free edge of said display board in such a manner as to cause said boards to move upon their pivots against the tension of their respective springs.

2. In a device of the character described, a support, a shaft mounted in said support, a pair of spaced rings concentrically positioned with respect to said shaft, a plurality of display boards pivotally supported between said rings, a spring secured to each of said boards and to said shaft, for the purpose of maintaining said boards in radial

alignment with respect to said shaft, means for rotating said shaft, a roller adapted to successively contact the free edges of said display boards so as to cause said boards to move upon their pivots and out of radial alignment with said shaft. ¹⁰

In testimony whereof I affix my signature.
ARTHUR B. CONNER
